TAPE SPLICER OR THE LIKE

Herman D. Post, Great Neck, and Edward Perper,
Brooklyn, N.Y., assignors to Robins Industries Corp.,
Flushing, N.Y.

Filed May 2, 1962, Ser. No. 69,949

Term of patent 14 years

(Cl. D61—1)

FIG. 1

FIG. 2

FIG. 3

FIG. 4

FIG. 1 is a side elevational view of a tape splicer showing our new design;

FIG. 2 is a front elevational view thereof;

FIG. 3 is a top plan view thereof; and

FIG. 4 is a rear elevational view thereof.

The dominant features of our design reside in the portions shown in full lines.

We claim:

The ornamental design for a tape splicer or the like, as shown and described.
